ELECTRIC FURNACE.

1,412,512.

Specification of Letters Patent. Patented Apr. 11, 1922.

Application filed April 23, 1920. Serial No. 375,951.

To all whom it may concern:

Be it known that I, ORA A. COLBY, a citizen of the United States, and a resident of Irwin, in the county of Westmoreland and State of Pennsylvania, have invented a new and useful Improvement in Electric Furnaces, of which the following is a specification.

My invention relates to electric furnaces and particularly to high-temperature furnaces of the electric-resistance type and it has for one of its objects to provide an electric-resistance furnace adapted to operate for comparatively long periods of time at relatively high temperature for annealing and heat treating of metal objects.

Another object is to provide a furnace of this type that shall employ solid blocks of refractory electrical-conducting material for the resistor and that shall embody improved means for conducting current to and from the resistor.

Another object is to provide a furnace so constructed that the block resistors shall support the roof of the chamber, whereby a lower contact resistance is obtained between the resistor and the terminal electrodes which operatively engage the resistors.

Another object is to still further reduce the contact resistance between the electrodes and the resistor by providing an auxiliary current path of relatively low resistance therebetween, which current path may be easily and quickly renewed.

Another object is to provide a resistor which shall comprise a plurality of solid blocks of electrical-conducting refractory material, such as may be purchased in the open market so that the possibility of failure of the complete resistor is slight.

In practicing my invention, I provide a chamber in a refractory casing, the solid blocks of refractory electrical-conducting material comprising the resistor forming the side walls of the chamber. I provide auxiliary recesses in the casing adjacent the ends of the resistor blocks and locate therein solid terminal electrodes and a mass of granular electrical material operatively connecting the electrodes and the resistor blocks. I provide means whereby the granular electrical-conducting material may be easily and quickly renewed when it has been

consumed during the operation of the furnace.

In the single sheet of drawings, Figure 1 is a cross-sectional view of the furnace embodying my invention on the line I—I of Fig. 2, and Fig. 2 is a cross-sectional view on the line II—II of Fig. 1.

The supporting structure of the furnace comprises an exterior metal casing or frame 1, which encloses an outer shell 2 of heat-insulating brick and an inner shell 3 of fire brick. The vertical parts of the shell 3 are spaced apart to form a chamber 4. A resistor 5 comprises a plurality of bricks or slabs of carborundum or silicon carbide, these blocks being in substantially a vertical position at the sides of the chamber 4 and forming the side walls thereof. A terminal electrode 6 is placed beneath the lower end of the resistor blocks 5, and a similar electrode 7, of slightly different form of cross-section, is placed above the upper end of the resistor blocks 5, both of the terminal electrodes operatively engaging the ends of the resistor blocks. A substantially horizontal recess 8 is formed in the shell 3 outside of, and adjacent to, the lower terminal electrodes 6 and the lower end of the resistor blocks 5, and in this recess is placed a mass 9 of finely divided electrical-conducting granular material, such as graphite or coke. The material 9 is thoroughly packed or tamped into place so that it will carry a relatively large portion of the current which may flow through the resistor blocks 5 and owing to its relatively low resistance and owing to the fact that it provides a large number of contact members with the lower end of the resistor blocks 5, the energy loss in this granular material will be relatively small. An opening 10 is provided at the rear end of the furnace, coaxial with each of the recesses 8, to permit of access to the recess so that the granular material may be retamped whenever necessary or be entirely withdrawn and renewed whenever desired.

A suitable cover member 11 is provided for the opening 10 to retain the granular material in place in the recess 8.

Similar recesses 12 are provided outside of, and adjacent to, the upper end of the resistor blocks 5 and the terminal electrodes 7, these recesses being filled with granular electrical-conducting material 9, the same as

used in the recess 8 and for the same purpose. The recess 12 may extend to the upper surface of the furnace and, in this way, provide ready access to the recess and the 5 granular material contained therein so that it may be tamped or renewed whenever this becomes necessary.

A roof 13, formed of bricks or slabs of highly refractory material, is provided for 10 the chamber 4 and is so formed that it rests upon the upper terminal electrodes 7, forcing these into close operative engagement with the upper ends of the resistor blocks and also forcing the lower ends of the resistor blocks 5 into close operative engagement 15 with the terminal electrodes 6. This provides a means for reducing the contact resistance between the electrodes and the resistor blocks but, as the resistor blocks may 20 not expand and contract equally during repeated heating and cooling of the furnace, the contact between the carbon electrodes 6 and 7 and the resistor blocks 5 may vary 25 and, therefore, the granular material 9 is provided so that proper contact may be made, irrespective of the variations of length of the individual resistor blocks 5. A lifting member 14 is suitably secured to 30 the roof 13 to permit of removing and replacing the roof 13 whenever desired.

A metal terminal plate 15 is provided for each of the terminal electrodes 6 and 7, being located below the electrode 6 and above the electrode 7. The electrodes 6 and 7 may 35 consist of graphite or of amorphous carbon, and suitable connecting means may be used to connect the metal terminal plates thereto. A dead-air space 16 is provided adjacent to the outside of the resistor blocks 5 40 to reduce the amount of heat which is conducted away from the outside of the resistor blocks 5.

While I have indicated that each of the 45 sets of resistor blocks 5 is in a separate circuit, it is, of course, to be understood that the two sets of blocks may be connected in series if it is desired to apply a relatively higher voltage to the terminals of the furnace.

50 I thus provide a furnace of relatively high capacity in which the resistor comprises a relatively large number of individual blocks of refractory material. I provide, also, means for conducting the current from these 55 resistor blocks which shall insure a current flowing through all of the resistors in parallel, even though the individual blocks expand and contract different amounts. I provide also means for readily renewing the 60 granular current-conducting means, thus insuring that the furnaces may be operated for relatively long periods of time without being torn down and reassembled.

While I have shown a specific embodiment 65 of my invention, various changes may be

made therein without departing from the spirit and scope of my invention, and I desire that only such limitations shall be placed thereon as are imposed by the prior art or are specifically set forth in the appended claims. 70

I claim as my invention:

1. In an electric furnace, the combination with a chamber, of a resistor adjacent said chamber and forming the side wall thereof, electrodes operatively engaging the ends of said resistor, terminal members connected to said electrodes, and masses of electrical-conducting granular material operatively engaging the ends of said resistor and said 80 electrodes. 75

2. In an electric furnace, the combination with a chamber, of a resistor comprising solid bricks or blocks of refractory electrical-conducting material forming the side 85 walls of said chamber, solid carbonaceous terminal electrodes operatively engaging the ends of said resistor, and a mass of electrical-conducting granular material operatively engaging each of the electrodes and the adjacent resistor-end. 90

3. In an electric furnace, the combination with a chamber, of a resistor comprising solid bricks of refractory electrical-conducting material forming the side walls of said chamber, terminal electrodes adjacent the ends of said resistor, granular electrical-conducting material operatively engaging the ends of the resistor and the adjacent electrode, and a cover member for said chamber 100 adapted to cause said electrodes and said resistor to operatively engage each other. 95

4. In an electric furnace, the combination with a chamber, of a resistor comprising solid bricks or blocks of refractory electrical-conducting material forming the side 105 walls of said chamber, terminal electrodes adjacent the ends of said resistor, and a roof for said chamber, said resistor blocks and said electrodes being adapted to support said 110 roof in its operative position. 110

5. In an electric furnace, the combination with a heating chamber, of a resistor comprising solid blocks or bricks of refractory electrical-conducting material forming the 115 side walls of said chamber, terminal electrodes adjacent the ends of said resistor, masses of electrical conducting granular material operatively engaging the ends of said resistor and the adjacent electrodes, and a 120 roof for said chamber, said roof being supported by said resistor and said terminal electrodes. 120

6. In an electric furnace, the combination with a chamber and a roof for said chamber, of a resistor comprising solid bricks of refractory electrical-conducting material forming the side walls of said chamber, terminal electrodes adjacent to the ends of said resistor, said electrodes and said resistor be- 125 130

ing adapted to support said roof in its operative position and means for reducing the amount of heat conducted away from the sides of said resistor and said chamber.

5. 7. In an electrical furnace, the combination with a chamber, and a roof for said chamber, of a resistor comprising bricks of refractory material forming the side walls of the chamber, solid carbonaceous terminal 10 electrodes adjacent the ends of said resistor bricks, said resistor and said electrodes being adapted to support said roof in its operative position, a mass of electrical-conducting granular material operatively engaging the ends of said resistor blocks and said electrodes, and jacketing means adjacent said resistor blocks for reducing the amount of heat conducted away from the sides of said resistor and said chamber.

8. In an electric furnace, the combination 20 with a chamber, of a resistor comprising solid blocks of refractory electrical-conducting material located in a substantially vertical position and forming the side walls of said chamber, solid carbonaceous terminal 25 electrodes adjacent to, and operatively engaging the ends of, said resistor blocks, masses of electrical-conducting granular material located in the sides of said resistor blocks away from said chamber and operatively engaging the ends of said resistor blocks and the adjacent electrodes and a roof for said chamber, said roof being supported by said resistor and said electrodes.

In testimony whereof, I have hereunto 35 subscribed my name this 1st day of April, 1920.

ORA A. COLBY.
